CLAIM

We claim the ornamental design for a plant stem stripping tool, as shown and described.

DESCRIPTION

FIG. 1 is a perspective view of a stripping tool.

FIG. 2 is a side view of a first side of the stripping tool.

FIG. 3 is a side view of a second side of the stripping tool.

FIG. 4 is a side view of a third side of the stripping tool.

FIG. 5 is a side view of a fourth side of the stripping tool.

FIG. 6 is a top view of a top of the stripping tool.

FIG. 7 is a bottom view of a bottom of the stripping tool; and,

FIG. 8 is a perspective environmental view of the stripping tool.

The broken and dashed lines in the drawings indicated environmental subject matter and is unclaimed subject matter, and form no part of the claimed design.
